SAFETY DEVICE

John H. Brown, Wakefield, Mich.

Application March 23, 1943, Serial No. 480,238

5 Claims. (Cl. 212—70)

This invention relates to a safety device and has relation more particularly to a device of this kind for use in connection with a revolving portable crane or hoist, and it is primarily an object of the invention to provide a device of this kind which will push or force clear of the machine any person who may be in danger of being caught between revolving and stationary parts of the machine.

It is also an object of the invention to provide a safety structure arranged at the opposite sides of the supporting body for a revolving crane or hoist and wherein gate members are provided at opposite sides of said body and which are automatically moved out into protecting position upon swinging of the crane or hoist to one side or the other of the body.

The invention also has for an object to provide a safety device for use in connection with a swinging crane or hoist and wherein such device is automatically moved into effective or ineffective position by the revolving or turning of the crane or hoist.

The invention consists in the details of construction and in the combination and arrangement of the several parts of my improved safety device whereby certain important advantages are attained, as will be hereinafter more fully set forth.

In order that my invention may be better understood, I will now proceed to describe the same with reference to the accompanying drawings, wherein:

Figure 1 is a view in top plan and of a somewhat diagrammatic character illustrating a safety device constructed in accordance with an embodiment of my invention.

Figure 2 is a view in side elevation of the structure as illustrated in Figure 1.

Figure 3 is a view in plan of the trackway as herein comprised, unapplied.

Figure 4 is a detailed sectional view taken substantially on the line 4—4 of Figure 2 and on an enlarged scale.

Figure 5 is an enlarged detailed sectional view taken substantially on the line 5—5 of Figure 4.

Figure 6 is a transverse sectional view taken substantially on the line 6—6 of Figure 5.

Figure 7 is a view, partly in elevation and partly in section, of one of the gates or guards as herein embodied, and

Figure 8 is a detailed sectional view taken substantially on the line 8—8 of Figure 1.

As disclosed in the accompanying drawings, B denotes a portable body of the type used in

connection with a locomotive crane or the like. As the particular construction of this body B forms no part of this invention, a detailed description thereof is believed to be unnecessary.

5 Mounted upon this body B in a well known manner for swinging or turning movement into effective or working position beyond either side of the body B is a crane or hoisting structure H.

Substantially surrounding the base portion of 10 the crane or hoist H and underlying the same is a continuous trackway T rigidly held to the base of the crane or hoist H by the bracket arms 1 or otherwise as may be preferred. As is particularly illustrated in Figure 3 of the drawings, 15 it is to be noted that this trackway T is in simulation somewhat of an ellipse, the configuration of the trackway, however, being such as to assure the desired swinging movement of the gates or guards G as the crane or hoist H is turned.

20 Each of these gates or guards G is of desired length and comprises upper and lower elongated bars 2 having interposed therebetween the braces or strengthening members 3. At one end of each gate or guard G, the members 2 are connected by

25 the vertically disposed tubular post or cross member 4 which is pivotally engaged with and between the vertically spaced and outstanding brackets 5 carried by the body B at a desired point thereon with respect to the crane or hoist H.

30 The opposite end of the gate or guard G is provided with an upstanding post 6 carried by a grooved wheel or pulley 7 which rides along the trackway T.

In the present embodiment of my invention 35 there are two guards or gates G at each side of the body B and with the guards or gates G at each side having their hinged ends remote from each other and substantially equidistantly spaced from the transverse center of the crane or hoist

40 H when said crane or hoist H is substantially at right angles to the body B, as illustrated in Figure 1. Each of these guards or gates G is also of a length desired to assure a maximum of safety.

45 Each of the guards or gates G in relatively close proximity to its hinged or pivoted end is provided with an additional post 8 interposed between and rigidly secured to the members 2. This post 8, as illustrated in Figure 1, is surrounded by a sleeve 9 provided at its central portion with an inwardly directed bracket or lug

10. Suitably secured to this bracket or lug 10 is an end portion of a flexible member 11, herein disclosed as a chain. This chain 11 extends transversely of and below the body B and has

its inner end portion secured, as at 12, to the intermediate or base portion of an elongated and relatively narrow U-bolt 14. The free extremities of the arms 15 of the U-bolt 14 are directed through a plate 16 and threading on said extremities of the arms 15 outwardly of the plate 16 are the heads or nuts 17 contacting with the outer face of the plate 16.

The gates or guards G, fore and aft of the crane or hoist H, have their pivotal mountings substantially in alignment transversely of the body B and the U-bolt 14 with which one chain 11 is connected is reversed with respect to the second U-bolt 14 and with the major free portions of the arms 15 of one U-bolt 14 substantially in parallelism with the arms 15 of the second U-bolt 14. The arms 15 of one U-bolt 14, as herein disclosed, are substantially at a quarter turn with respect to the arms 15 of the second U-bolt 14.

Surrounding the substantially parallel portions of the arms 15 of the U-bolts 14 is an expansible coiled spring 18 of requisite tension and which has its opposite extremities contacting the inner or opposed faces of the plates 16, whereby constant pull is urged upon the flexible members or chains 11 to effect desired inward swinging movement of the gates or guards G, thus maintaining the grooved wheels or pulleys 7 in desired effective contact from without with the trackway T.

When the crane or hoist H is in its straight-away or ineffective position, as illustrated in Figure 2, the guards or gates G will lie close against the sides of the body B, but as the crane or hoist H is swung or turned to extend laterally beyond one side of the body B, the guards or gates G at such side will be also swung outwardly, as illustrated in Figure 1, while the guards or gates G at the opposite sides will still remain in positions closely adjacent to the body B. It will be obvious, however, that should the crane or hoist H be swung out laterally beyond the opposite side of the body B, the gates or guards G at that side will be swung outwardly and the gates or guards G at the other side will be maintained in their retracted positions.

It is believed to be obvious from the foregoing that the safety means as herein provided effectively guard a person against injury as the result of being caught between a revolving or turning part and a stationary part of the crane or hoisting apparatus, and that it is particularly effective in pushing a workman or other person clear of the crane or hoist when revolving should he be otherwise in danger of being crushed.

From the foregoing description it is thought to be obvious that a safety device constructed in accordance with my invention is particularly well adapted for use by reason of the convenience and facility with which it may be assembled and operated.

What is claimed is:

1. The combination with a supporting body and a structure mounted thereon for turning movement to swing to positions beyond opposite sides of the body; a pair of gates pivotally attached to each of said opposite sides of the body to swing into positions substantially parallel with the adjacent side of the body, the pivot for each pair of gates having positions fore and aft of the turning axis for said structure, an endless trackway encircling the lower portion of the pivoted structure, an anti-friction connection between each gate and the trackway whereby the gates will be swung outwardly away from the body upon movement of the pivoted structure to a position transversely of the body, and resilient means normally urging swinging of the gates inwardly toward the body.
2. The combination as set forth in claim 1, in which said anti-friction element comprises a grooved roller carried by each of the gates to receive the said trackway.
3. The combination as set forth in claim 1, in which the said means urging the gates to swing inwardly toward the body comprises resilient couplings extending transversely of the body and connecting each of the gates of one pair with the corresponding opposite gate of the other pair.
4. The combination with a body and a structure mounted thereon for turning movement to swing to a position laterally beyond either of two opposite sides of the body; of a pair of relatively long gates disposed at each of the said opposite sides of the body and pivotally attached to the body at their remote ends to swing laterally outwardly, the adjacent ends of each pair of gates being in opposed relatively closely spaced relation when the gates are in closed position, an endless track carried by and encircling the lower portion of said structure, a peripherally grooved roller rotatably supported upon the free end of each gate and having said trackway permanently engaged in the groove thereof, said gates being swung outwardly away from the body by the endless track upon turning of the structure toward a position transversely of the body, guides extending transversely of the body between corresponding gates of each pair, and a spring coupling extending through each guide and connecting together the oppositely positioned corresponding gates of each pair and constantly urging the swinging of said gates inwardly toward the body.
5. The combination as set forth in claim 4, in which the said spring connection between opposite gates comprises a central unit consisting of a pair of opposed plates, a yoke connected with each plate and extending through the other plate, a chain connection between each yoke and the adjacent gate, and a compression spring encircling the yokes between said plates and normally urging the plates apart.

JOHN H. BROWN.
